FLUID ACTUATED CIRCUIT CLOSER

Wilbert W. Mays, Middletown, Pa.

Application April 17, 1942, Serial No. 439,419

1 Claim. (Cl. 200—82)

This invention relates to a signal operating means and pertains particularly to a hydraulic stop light switch or signal circuit controller for connection with any standard type of master cylinder in a fluid brake system, or with any other part of the system where fluid pressure is developed upon the application of the brakes.

The principal object of the present invention is to provide a simply constructed but strong and durable hydraulic switch which can be relied upon to operate at all times when it is properly connected in a hydraulic brake system to receive pressure therefrom so that the operation of the vehicle brake light will always be assured.

Another object of the invention is to provide a fluid or hydraulic switch structure which can be inexpensively manufactured and which can also be easily and quickly assembled or disassembled as required so that the device may be set up and put into operation with a minimum expenditure of time and effort.

The invention will be best understood from a consideration of the following detailed description taken in connection with the accompanying drawing, it being understood, however, that the invention is not to be considered as limited by the specific illustration or description but that such illustration and description constitute a preferred embodiment of the invention.

In the drawing:

Figure 1 is a vertical longitudinal section through the switch structure embodying the present invention.

Figure 2 is a transverse section on the line 2—2 of Figure 1.

Figure 3 is a transverse section on the line 3—3 of Figure 1.

Figure 4 is a detailed top plan view of one of the elements of the switch unit per se.

Figure 5 illustrates one manner of connecting the switch with a master cylinder and shows a signal circuit diagram in which circuit the switch is connected.

Referring now more particularly to the drawing, it will be seen upon reference to Figure 1 that the switch comprises the two separably joined sections 1 and 2. Both of these sections are of polygonal exterior cross-section, and the section 1 comprises a cylinder having a piston chamber 3 formed axially therein and opening through one end thereof. The end of the cylinder through which the chamber opens has the axially extending exteriorly threaded flange or nipple 4, while at the opposite end of the cylinder there is formed the axial nipple of smaller exter-

nal diameter than the nipple 4 and indicated by the numeral 5, which is exteriorly threaded for connection at a suitable point in the hydraulic brake system. This attaching nipple 5 has a small bore 6 therethrough by way of which fluid under pressure may enter the piston chamber 3.

The piston chamber 3 is provided near the upper end, or that end from which the nipple 4 extends, with the annular wall groove or channel 7 in which is fitted a slit stop ring 8, the ends of which have the inwardly directed fingers 9, the function of which is hereinafter set forth.

The portion 2 of the switch body is in the form of an elongated tubular shell which is open at one end and provided with the interiorly reduced threaded portion 10 in which the nipple 4 is received. The interior of the shell provides a chamber 11 which is substantially the same diameter as the piston chamber 3, and the end wall of the shell 2 has two longitudinally extending passages 12 formed therethrough for the purpose hereinafter described.

Extending from the open end of the tubular shell are the diametrically opposed longitudinal slots 13 in which are slidably engaged the ends of a guide spider 14, the central portion of which is enlarged, as indicated at 15, and provided with a piston stem guide 16.

Within the piston chamber 3 is closely fitted a solid piston 17. This is interposed between the stop ring 8 and that end of the chamber from which the bore 3 leads. A stem 18 is carried by the piston 17 and extends longitudinally through the aligned chamber to and through the guide 16, as shown.

Secured to the piston stem 18 is a collar 19 and interposed between this collar and the spider 14 is a compression spring 20 which constantly urges the piston to move into the piston chamber 3 toward the bore 6.

The free end of the piston rod 18 is reduced and threaded to have threadably secured thereon the contact head 21 which is formed of a suitable insulation material.

Within the upper end of the chamber 11 is fitted an insulation liner 22 which covers the end wall and a portion of the side wall. This liner has integrally formed therewith the sleeves 23, each of which extends through a passage 12 to form an insulation lining over the wall thereof.

The numeral 24 generally designates an element of the switch unit. There are two of these elements in the unit and each element comprises a post 25 around one-half of the lower end of which is a spacer flange 26. From the said lower

end there also extends, oppositely from the flange 26, the resilient contact finger 27. The post 25 is adapted to be extended through a sleeve 23 to extend beyond the upper end of the shell, and the upper end of the post is provided with the axial bore 28 which is tapped to receive a binding screw 29. Exterioly the upper end of each post 25 is threaded to receive a securing nut 30 and between this nut and the end of the shell is interposed an insulation washer 31. By means 10 of the nut the post is drawn tightly into position and the terminal or contact 27 is disposed within the shell to extend axially so that its free end is located adjacent the axial center of the chamber. The terminal fingers 27 are shaped so that one terminates in a downwardly turned portion 27' while the other one terminates in an upwardly extending portion 27" and these oppositely directed portions are arranged in spaced aligned relation and, being upon the axial center of the chamber 44, are in line with the insulation head 24 of the piston stem 43. Thus, when fluid under sufficient pressure is introduced into the piston chamber 3 below the piston, to force the stem upwardly, this insulation head will contact the adjacent terminal finger 27 and flex it upwardly into flexible contact with the overlying finger so as to effect the closing of the electrical signal circuit 32, Figure 5, in which the switch unit terminals or elements are connected.

While both of the terminals 27 are flexible so that excessive pressure on the lowermost terminal will not damage the switch due to the fact that the upper terminal will also yield, the stop ring 8 is so located in the piston chamber as to limit the upward movement of the piston. This upward movement of the piston is made against the resistance of the spring 20 and, consequently, when the fluid pressure is reduced sufficiently the spring will take control and return the piston to its former position, thus allowing the tips 27' and 27" to separate and thus open the signal circuit 32.

In Figure 5 the circuit closing device is shown coupled with a master cylinder C of a hydraulic brake system; but it is to be understood that the device may be used at any other suitable location in the system where the desired fluid pres-

sure is obtainable for introduction through the passage 6 to the piston chamber 3 for the purpose of actuating the piston when the brakes are applied.

From the foregoing it will be readily apparent that the device herein described is of simple construction but may be strongly made so as to give long and reliable service. If, for any reason, access must be had to the interior of the device for making repairs or adjustments this may be readily accomplished by unscrewing the tubular shell portion 2 from the cylinder portion 1, whereupon all of the parts can be easily reached.

I claim:

A circuit closer unit comprising a pair of bodies, each having an axial chamber opening through one end, means detachably coupling the bodies together to axially join said chambers, a piston disposed within the chamber of one body and having an integral stem extending axially into the chamber of the other body, means for coupling the said one body with a source of fluid under pressure for the introduction of fluid into the chamber of the said one body between the piston and the adjacent end wall of the body, a split ring fitted within the chamber of the one body upon the opposite side of the piston from the fluid introducing means, the extremities of the split ring having inwardly directed fingers for limiting the operative movement of the piston, a pair of terminal posts extending through the end wall of the other body and each carrying upon its inner end a resilient contact finger, said contact fingers being arranged in end overlapping spaced relation upon the axial center of the chamber and in the line of the piston stem, one of said fingers being engaged by the piston stem upon movement of the piston under fluid pressure to bring said fingers into electrical contact, a guide member extending transversely of the chamber of the said other body and having the piston stem slidably extended therethrough, a collar integral with the piston stem and spaced from said guide, and a spring interposed between the collar and guide and constantly urging movement of the piston away from said contact fingers.

WILBURT W. MAYS.
